UNITED STATES PATENT OFFICE

OTTO E. SZEKELY AND RUSSELL H. JOHNSON, OF HOLLAND, MICHIGAN

PISTON-RING-SPRING MACHINE

Application filed September 23, 1927. Serial No. 221,440.

This invention relates to machines for making inner ring springs for piston rings of the conventional type and it is particularly adapted for making inner ring springs such disclosed in the co-pending application of Otto E. Szekely, Ser. No. 33,938, filed June 1, 1925.

The object of the invention is to provide a machine which is capable of making two inner ring springs at the same time and which will crimp the flat stock at certain intervals so that each crimp will have the same radius.

Another object is to provide a machine which will cut the ring from a roll of flat stock which ordinarily comes wound on spools, so that the ends of the finished ring will be at the center of one of the crimps.

Another object is to provide a machine having novel and improved feeding rollers which are adjustable and removable whereby the diameter of the main roll determines the size of the finished inner ring.

And a further object is to provide a machine which is simple and compact, which is efficient and accurate, and which can be readily and economically manufactured.

A selected embodiment of the invention is shown in the accompanying drawings in which,

Fig. 1 is a transverse sectional view taken on the center line of the main drive shaft.

Fig. 2 is a similar view taken on the center line of the forming dies.

Fig. 3 is a longitudinal sectional view taken through the center line of the feed roller, and

Fig. 4 is a sectional view taken longitudinally of the machine.

Referring to the drawings 1 designates the machine base which supports the frame 2 in which there is mounted a transverse shaft 3 carrying the pulleys 4 and 5. The pulley 4 is keyed to the shaft while the pulley 5 is loose in the usual manner. A suitable belt (not shown) is connected with a driving shaft and drives the fixed pulley which transmits the power to the shaft 3.

A mitre gear 6 fixed to the drive shaft meshes with another mitre gear 7 fixed on the vertical shaft 8 and rotates this vertical

shaft. A gear 9 fixed to the shaft 8 drives a gear 10 through an idler gear 11, Fig. 4. Another vertical shaft 12 Fig. 3 carrying the gear 10 drives the worm shaft 13 which may be connected to the shaft 12 by a coupling 14 and the shaft 13 is adapted to have vertical movement relative to the shaft 12. The worm shaft 13 drives the worm gear 15 on the shaft 16 suitably mounted in the gear box 17, which is connected to the frame 2 and adapted to have vertical movement relative to the frame, being fastened to the frame by bolts entering slots therein (not shown). The shaft 16 and the shaft 18 of the feed roller 19 are connected together by a coupling 20. The roller 19 comes in various diameters depending upon the size of the inner ring to be made and the vertical movement of the gear box and the gears provides the necessary adjustment to accommodate these various sized rollers. The roller 19 bears against an idler roller 21 mounted in anti-friction bearings 22 arranged in the frame, and the roller shaft 18 runs in bronze bearings 23 at the top only, as the lower part of the roller 19 is supported upon the idler roller 21.

A yoke 24 Fig. 3 arranged in the frame 2 is provided with sockets 25 which accommodate the springs 26 which bear on the top of the bearings 23, as shown in Fig. 3. Compression of the springs 26 is furnished by the studs 27 and the screw 28 which is locked by the knurled nut 29 Figs. 3 and 4 to keep the roller 19 in tight operative relation with the idler roller 21.

A worm wheel 30 Fig. 4 fixed to the shaft 31 which is mounted in suitable bearings in the frame 2 is driven by a worm 32 fixed to the main drive shaft 3. A forming roller 33 held to the shaft 31 by keys 34 Fig. 2 and rotatable therewith is provided with a plurality of integral projections 35, there being as many of these projections 35 as there are to be crimps formed in the finished inner ring spring.

The forming roller 33 turns slowly due to the timing and the size of the operating gears and contacts with an operating roller 36 mounted to rotate freely in the guide 37. The guide 37 is slidably mounted on the ver-

tical guide pins 38 and 39 Fig. 2 and is pushed upward by the springs 40 resting on the lower bracket 41 rigid with the guide pins, and keeps the operating roller 36 always against the forming roller 33. An upper die 42 Fig. 4 is arranged in the guide 37 and adjacent the operating roller 36, from which it receives its motion so that when the teeth 35 of the forming roller 33 engage the operating roller 36 there is free vertical motion between the upper die 42 and the lower die 43 which is rigidly mounted on the bracket 41. A bar 44 Fig. 4 loosely connected to the upper die 42 and spaced therefrom by the springs 45 comes in contact with the inner ring stock 46 before the stock is touched by the upper die. This bar holds the stock 46 against the lower die 43 while the crimping operation takes place. When the upper die recedes, or raises upwardly, the bar 44 will hold the stock in position for a slight predetermined distance which is equivalent to the play of the loose connection between the bar and the upper die, after which it will move upward with the upper die and allow the stock to be fed through the dies for the next crimping operation. The lower die 43 is rounded as at 47, Fig. 4, and engages the slots 48 in the upper die to give the correct desired curvature or crimp to the inner ring spring.

The upper die also carries shear blades 49 which register with slots in the lower die 43 so that when the inner ring is complete it can be cut from the stock. This is accomplished by providing one of the projections 35 on the forming wheel 33 longer than the other projections so that at the proper time the longer projection forces the upper die farther down than usual and causes the blades 49 to cut the material. The lower die 43 and the bracket 41 have a slot provided therein to allow any slugs cut therefrom to fall through and prevent possible jamming of the machine.

The machine may also be provided with a pair of felt blocks 50 Fig. 4 held in the clamp 51 and arranged in front of the feeding rollers to remove any dirt from the stock.

After the rings are completed and cut from the stock they are directed out of the machine by the lower side guide 52 and the side guides 53.

The machine has been designed to make two inner rings at one time which is more expedient than making only one at a time, while more than two may cause complications due to the extra mechanism required although it is possible to make more than two springs at one time and the invention is not limited in this respect.

The operation of the machine is as follows: The stock 46 is fed between the main roller 19 and the idler 21, the parts being so timed and constructed so that one complete revolution of the roller 19 will determine the size of the finished inner ring. The

stock is thus fed to the dies 42 and 43 where the forming roller will cause the stock to be crimped at certain spaced intervals, in this instance 6, when the longer projection 35 on the forming roller 33 will cause the shear blades to cut the stock at the center of the last crimp thereby providing a hexagonal spring inner ring having 6 crimps of equal radii one of which is cut at the center.

The longer one of the projections 35 is spaced at an unequal distance in relation to the other projection 35, because if this longer projection were spaced the same distance from the other projections, the roller would naturally either cause a larger crimp to be made in the ring, due to the further movement of the stock relative to the roller, or the crimp would be spaced unequally relative to the other crimps of the ring. As it is desirable to have the crimps equally spaced relative to each other the longer projection on the forming roller 33 has been spaced an unequal distance relative to the other projections to accomplish this result.

Changes may be made in form, construction and arrangement of the parts without departing from the spirit of the invention or sacrificing any of its advantages and the right is hereby reserved to make all such changes as fairly fall within the scope of the following claims.

We claim:

1. A machine for making piston rings comprising a base, a frame, rollers in said frame for feeding material to the machine, means for rotating one of said rollers, a forming roller, means driven by said first named means for driving the forming roller, an upper movable die, a stationary lower die, an operating roller cooperating with said forming roller for reciprocating said upper die, and means arranged in said upper die for cutting the material after it has been crimped.

2. A machine for making piston ring springs comprising a base, a frame, a driven feed roller, an idler roller, means arranged in front of said rollers for feeding material thereto, means for driving said feed roller, a forming roller having projections thereon, an operating roller, an upper die cooperating with said operating roller and adapted to be reciprocated due to the projections on the forming roller, a rigidly mounted lower die whereby said material is intermittently crimped upon each reciprocation of the upper die, and shearing plates arranged in the upper die for cutting the material at the center of one of the crimps at each revolution of the forming die.

3. A machine for making piston ring springs comprising a base, a frame, a drive shaft mounted in said frame, a forming roller mounted in said frame, means operated by said shaft for driving said forming roller, vertical guide pins fixed to said frame, a

guide slidably mounted on said pins, an operating roller mounted in said guide and operated by said forming roller to reciprocate said guide, an upper die arranged on said guide and adapted to reciprocate therewith, a bar loosely connected to said guide, a lower die rigidly secured to said pins, and means for feeding material to said guides to be crimped at predetermined spaced intervals.

10 4. A machine for making piston ring springs comprising a base, a frame, a feed roller and an idler arranged in said frame for feeding material to the machine, the diameter of the feed roller determining the size of the finished ring, a forming roller having a plurality of integral projections for crimping the material, the number of projections determining the number of crimps to be made, guide pins fixed to said base and said frame, a guide slidably mounted on said guide pins, an upper die arranged in said guide, an operating roller mounted in said guide and operated by said forming roller to reciprocate said upper die and, a lower die rigidly supported in said frame, whereby the material is crimped by said dies.

5. A machine for making piston ring springs comprising a base, a frame, a feed roller and an idler arranged in said frame for feeding material to the machine, the diameter of the feed roller determining the size of the finished ring, a forming roller having a plurality of integral projections for crimping the material, the number of projections determining the number of crimps, guide pins fixed to said base and said frame, a guide slidably mounted on said guide pins, an upper die arranged in said guide, an operating roller mounted in said guide and operated by said forming roller to reciprocate said upper die, a lower die rigidly supported in said frame whereby the material is crimped as it is fed between said dies, and means operated by said upper die to cut the material after each complete revolution of the forming roller.

6. A machine for making piston ring springs comprising a base, a frame, a feed roller and an idler arranged in said frame for feeding material to the machine, the diameter of the feed roller determining the size of the finished ring, a forming roller having a plurality of integral projections to crimp the material, one of said projections being longer than the others, the number of projections determining the number of crimps, guide pins fixed to said base and said frame, a guide slidably mounted on said guide pins, an upper die arranged in said guide, an operating roller mounted in said guide and operated by said forming roller to reciprocate said upper die, a lower die rigidly supported in said frame whereby the material is crimped as it is fed between the dies, and means arranged in the upper die and

controlled by the longer projection on the forming wheel to cut the material at the center of one of the crimps.

7. A machine for making piston ring springs comprising a base, a frame, a feed roller and an idler arranged in said frame to feed material to the machine, the diameter of the feed roller determining the size of the finished ring, a forming roller having a plurality of integral projections to crimp the material, the number of projections determining the number of crimps, guide pins fixed to said base and said frame, a guide slidably mounted on said guide pins, an upper die arranged in said guide, an operating roller mounted in said guide and operated by said forming roller to reciprocate said upper die, a lower die rigidly supported in said frame whereby the material is crimped between said dies as it is fed therethrough, means operated by said upper die to cut the material after each complete revolution of the forming roller, and means operatively connected to the upper die for holding the material against the lower die.

8. A machine for making piston ring springs comprising a base, a frame, a feed roller and an idler arranged in said frame to feed material to the machine, the diameter of the feed roller determining the size of the finished ring, a forming roller having a plurality of integral projections to crimp the material, one of said projections being longer than the others, the number of projections determining the number of crimps, guide pins fixed to said base and said frame, a guide slidably mounted on said guide pins, an upper die arranged in said guide, an operating roller mounted in said guide meshing with and operated by said forming roller to reciprocate said upper die, a lower die rigidly supported in said frame whereby the material is crimped as it is fed between said dies, and shear blades connected to said upper die and adapted to engage slots in said lower die to cut the material, said blades being operated by engagement of the longer projection with the operating roller to further move the upper die.

9. A machine for making piston ring springs comprising a base, a frame, a feed roller and an idler arranged in said frame to feed material to the machine, the diameter of the feed roller determining the size of the finished ring, a forming roller having a plurality of integral projections to crimp the material, one of said projections being longer than the others, the number of projections determining the number of crimps, guide pins fixed to said base and said frame, a guide slidably mounted on said guide pins, an upper die arranged in said guide, an operating roller mounted in said guide meshing with and operated by said forming roller to reciprocate said upper die, a lower die rigid-

- ly supported in said frame whereby the material is crimped as it is fed between said dies, shear blades connected to said upper die and adapted to engage slots in said lower die to cut the material, said blades being 5 operated by engagement of the longer projection with the operating roller to further move the upper die, and means arranged in front of said feed roller to clean the material as it is being fed to the machine.
- 10 10. A machine for making piston ring springs comprising a base, a frame, a feed roller and an idler arranged in said frame to feed material to the machine, the diameter of 15 the feed roller determining the size of the finished ring, a forming roller having a plurality of integral projections to crimp the material, one of said projections being longer than the others, the number of projections determining the number of crimps, guide pins fixed 20 to said base and said frame, a guide slidably mounted on said guide pins, an upper die arranged in said guide, an operating roller mounted in said guide meshing with and operated by said forming roller to reciprocate said upper die, a lower die rigidly supported in said frame whereby the material is crimped as it is fed between said dies, shear 25 blades connected to said upper die and adapted to engage slots in said lower die to cut the material at the center of one of the crimps, said blades being operated by engagement of the longer projection with the operating roller to further move the upper die, means arranged 30 in front of said feed roller to clean the material as it is being fed to the machine, and means operatively connected to said upper die for holding the material in crimping position.
- 35 11. A machine for making piston ring springs comprising a base, a frame, a feed roller and an idler arranged in said frame to feed material to the machine, the diameter of the feed roller determining the size of the finished ring, a forming roller having a plurality 40 of integral projections to crimp the material, one of said projections being longer than the others, the number of projections determining the number of crimps to be made, guide pins fixed to said base and said frame, a guide 45 slidably mounted on said guide pins, an upper die arranged in said guide, an operating roller mounted in said guide meshing with the forming roller and operated thereby to reciprocate said upper die, a lower die rigidly supported in said frame whereby the material is crimped as it is fed between the dies to 50 crimp the material, shear blades connected to said upper die and adapted to engage slots in said lower die to cut the material at the center of one of the crimps, said blades being operated by engagement of the longer projection with the operating roller to further move the upper die, means arranged 55 in front of said feed roller to clean the material as it is being fed to the machine.
- 60 12. A machine for making piston ring springs comprising a base, a frame, a feed roller and an idler arranged in said frame to feed material to the machine, the diameter of the feed roller determining the size of the finished ring, a forming roller having a plurality 65 of integral projections to crimp the material, one of said projections being longer than the others, the number of projections determining the number of crimps to be made, guide pins fixed to said base and said frame, a guide slidably mounted on said guide pins, an upper die arranged in said guide, an operating roller mounted in said guide meshing with the forming roller and operated thereby to reciprocate said upper die, a lower die rigidly supported in said frame whereby the material is crimped as it is fed between the dies to crimp the material, shear blades connected to said upper die and adapted to engage slots in said lower die to cut the material at the center of one of the crimps, said blades being operated by engagement of the longer projection with the operating roller to further move the upper die, means arranged in front of said feed roller to clean the material as it is being

fed to the machine, means operatively connected to said upper die for holding the material in crimping position, and guides arranged below the lower die for directing the finished ring away from the dies.

70

12. In combination with a piston ring machine, of a forming roller therefor comprising projections on said roller for crimping inner ring material, one of said projections being spaced unequally relative to said other projections, so that each crimp in the finished ring will be spaced equally from each other.

75

13. A forming roller for piston ring machines having a plurality of projections thereon, one of which is longer than said other projections, and shear blades controlled by said longer projection, said longer projection being spaced at an unequal distance relative to said other projections, whereby the stock which is to be crimped by said projections will have the crimps equally spaced.

80

14. A machine for making piston ring springs comprising a base, a frame, means for providing a continuous feed of stock to the machine, means for making a predetermined number of crimps in the stock at spaced intervals, each crimp having the same radius, said crimping means comprising a lower fixed die and an upper reciprocable die, and means on said upper die for cutting the finished ring from the stock after the last crimp has been made and while the upper die remains in clamping relation with the lower die so that each ring will be divided at the center of the crimp.
